UNITED STATES PATENT OFFICE.

JOHN F. W. SCHMIDT, OF OSHKOSH, WISCONSIN.

DESIGN FOR A BOAT-CLEAT.

SPECIFICATION forming part of Design No. 35,031, dated September 3, 1901.

Application filed August 8, 1901. Serial No. 71,412. Term of patent 14 years.

To all whom it may concern:

Be it known that I, JOHN F. W. SCHMIDT, a citizen of the United States, residing at Oshkosh, in the county of Winnebago and State 5 of Wisconsin, have invented and produced a certain new and original Design for Boat-Cleats; and I do declare the following to be a full, clear, and exact description of the invention, such as will enable others skilled in 10 the art to which it appertains to make and use the same.

The invention relates to a new and original design for a boat-cleat; and it consists of the design shown in the accompanying drawings, 15 in which—

Figure 1 is a perspective view, and Fig. 2 is an end view.

The leading features of the design consist

of an attaching-base A, a thick short standard B, oppositely-projecting inclined arms D, 20 beveled on their upper faces, a thick neck E, and oppositely-projecting arms F, beveled on their lower faces and arranged above the arms D and forming therebetween openings contracting from their entrances to the neck E. 25

What I claim is—

The design for a boat-cleat, as herein shown and described.

In testimony whereof I have hereunto set my hand in presence of two subscribing witnesses. 30

JOHN F. W. SCHMIDT.
